UNITED STATES PATENT OFFICE.

THEODORE G. BAUGH, OF LAKE PLACID, NEW YORK.

ELECTRIC HEATER.

Application filed May 5, 1925. Serial No. 28,139.

This invention relates to improvements in electric heaters, having for an object to provide a novel form of heater wherein a forced draft by the heating means of the same will be effected, hence, permitting of radiation of greater heat and generally, increasing the efficiency of the device.

It is likewise an object of the invention to provide a heater wherein a novel form of cover or hood is employed, the same being of such construction as will constrict the outlet way for the heated air, thereby causing the same to act as a fluid piston and assist in the establishing of a forced draft through the device and by the heating means.

It is also an equally important object of the invention to provide a heater with means for dissipating the currents and the heat occurring at the bottom of the same and adjacent the point of communication of the heating chamber with the cold air inlet ways in order that the downward passage of such air and its discharge into the heating chamber will not be impeded by contact with a surface of high temperature, hence ensuring the full circulation of air through the device, first, its downward passage when cold, through the ways therefor into the heating chamber, and with heating, immediately followed by upward passage of the same through the heating chamber and from the device.

Among other aims and objects of the invention may be recited the provision of a heating device of the character mentioned whose walls of the housing thereof and walls of the jacket of the same are formed to provide heat insulation means whereby such walls will be kept cool and in consequence, provide for a cool passage way or inlet way for the cool air flowing into the heating chamber of the device, ensuring the downward passage of such air into the housing of the device to a point in proximity to the bottom of the same, whereupon it is then discharged into the jacket the interior of which constitutes the heating chamber.

Other objects of the invention will be in part obvious, and in part pointed out hereinafter.

In order that the invention and its mode of operation may be readily understood by persons skilled in the art, I have in the accompanying illustrative drawings, and in the detailed following description based

thereupon, set out one embodiment of the same.

In these drawings:

Figure 1 is a vertical section through the improved device;

Figure 2 is a fragmentary top plan view of the same with the hood or cover applied; and,

Figure 3 is a similar view wherein the hood or cover has been removed, showing in detail, the arrangement of the heating element with respect to the open upper end of the heating chamber or jacket of the device.

Having more particular reference to the drawings, in connection with which like characters of reference will designate corresponding parts throughout, the improved heater may be stated to comprise a shell-like casing designated in its entirety herein by the numeral 1, the lower or bottom portion of such shell being provided with outwardly bent relatively spaced legs 2, while a bottom 3 is fixedly arranged in the lower end thereof, as is clearly shown in the Figure 1. A plurality of layers of heat insulating material designated herein, respectively, by the numerals 4, 5 and 6 are snugly received within the shell-like body 1 of the device upon the bottom 3 thereof, while over the upper face or side of the layer of heat insulating material 6, there is arranged a covering or projecting sheathing 7. Also, a sleeve of insulating material, indicated in its entirety by the numeral 8 is snugly received within the body or housing 1, being arranged adjacent to and extending parallel with the vertical side walls thereof. In this connection, it is of course to be understood that the heat insulating layers and sleeve 90 employed may be of various forms or construction, although it is desirable that the same provide for the usual dead air space as between the opposite walls of the same, suitable heat insulating material such as asbestos, or similar sheet material, being arranged therein. This insulating sleeve 8, as will be noted, rests upon the covering or sheathing 7 over the upper face of the up-

permost layer of heat insulating material 6 and the upper marginal portions of said sleeve extend to a point substantially flush with the upper marginal portions of the vertical sides of the housing 1, as is also clearly shown in the Figure 1. Furthermore, if desired, an inner facing or sheathing of metal or other suitable material, des-

gnated herein for the purpose of convenience by the numeral 9 is adapted to be received within the heat insulating sleeve 8, being arranged adjacent to the outer side of the same and extending over the marginal portions thereof as is shown in said Figure 1, into engagement with adjacent portions of the upper end of the vertical side walls of the housing 1.

10 A jacket, herein shown to be circular in cross section, is arranged within the housing 1, said jacket being preferably formed of metal of double wall formation as is clearly shown, and having heat insulating material 10 arranged between the walls thereof, corresponding to the construction and arrangement of the heat insulating material 8 aforesaid. This jacket 10 is supported at its lower end upon angle bracket arms 11, certain of whose ends are secured to the inner sides of the lower portions of the sleeve or sheathing 9, while the opposite ends thereof pass under the lower marginal portions of said jacket and are connected to adjacent portions of the same in a suitable manner. Thus, it will be understood that the jacket 10 will be supported in spaced relation with respect to the side walls of the housing of the device and likewise, that the bottom of 25 the same will be supported in spaced relation with respect to the bottom of such housing, that is, the sheathing 7 covering the heat insulating layers 4, 5 and 6. In consequence, it will be understood that a passage way is 30 afforded as between the vertical side walls of the housing 1 and the jacket 10 for the passage of cold air into the device downwardly with respect to the same to a point adjacent its bottom whereupon such cold air 35 will discharge upwardly into the jacket 10 constituting the heating chamber, as will be hereinafter apparent.

Also, it should be noted that the upper end of the jacket 10 is rigidly supported with respect to the corresponding portion of the housing 1 through the medium of other angle bracket arms 12, having connection with adjacent portions of said housing and the jacket 10; while the upper extremities of 50 said brackets are arranged approximately flush with the upper extremities of the vertical side walls of such housing 1.

An electric heating element 13 is supported in the open upper end of the jacket 10 and with the supplying of electrical energy thereto by way of the lead-in connections 14, it will be understood that effectual means will be provided for heating that air passing 55 upwardly through said jacket 10 and from 60 the open upper end thereof. At this point, it will be noted that the lead-in electrical connections 14 are passed through suitable insulating bushings 15 engaged in adjacent portions of the side walls of the housing 65 1 and the jacket 10, while a suitable form of

connection 16 is provided upon the outer side of the housing whereby electrical connection may be established with ordinary electrical conductors 17 or similar devices extending from a source of electrical energy, 70 not shown herein.

In order that the lower or bottom portion of the heating device will be prevented from reaching too high a temperature with the resultant impedance of the discharge of cold air from the cold air ways into the bottom of the jacket 10, a heat dissipating device in form of an inverted frusto-conical fin-like element 18 is provided, the same being formed with a concentrically arranged securing and supporting sleeve through which an anchoring or tying bolt 19 is passed, the lower end or shank portion of such bolt passing through an opening formed in the sheathing or covering 7 and one side of the heat insulating layer 6, whereupon a lock nut or other securing device 20 is engaged therewith. In this way, it will be understood that the heat dissipating device 18 will be rigidly secured in a fixed position with respect to the bottom of the heating device. Consequently, that heat radiated from the electrical resistance heating element 13 will be directed onto the various blades or fins of the dissipating device 18 and because of its absorption thereby, the heat will be prevented from being directly transmitted to the bottom of the improved heating device. Thus, the bringing of the bottom of such heating device to a temperature such as will 95 impede or interrupt the passage of cold air through the cold air ways of the device downwardly and into the lower end of the jacket 10 will be prevented.

Adapted to be normally supported upon 105 the upper end of the housing 1 and the jacket 10 is a drum-like cover or hood, generally indicated at this time by the numeral 21, said hood having a grid 22 engaged over the open upper end thereof, while a frusto-conical band or sleeve 23 is supported within the same concentrically thereof and is adapted to be snugly and frictionally engaged over a bevelled or diagonally disposed ring or band 24 fixedly secured to the 110 upper end of the jacket 10 through suitable securing devices. The outer side walls of the drum-like cover or hood 21 are adapted to have snug and frictional engagement over the outer sides of the upper end portion of the housing 1, as is clearly shown in the Figure 1 and consequently, it will be understood that with such downward engagement of the hood or cover 21 over said sides of the housing 1, the lower end of the frusto-conical sleeve 23 will engage with the outer surface of the ring 24 and thereby, the said hood or cover 21 and the sleeve 23 will find 115 stable and practical support.

120 The sleeve 23, as will be noted, constricts 125 130

the outlet way from the jacket 10 comprising the heating chamber of the improved device and because of this constricted outlet passage for the heated air passing from the heating chamber or jacket 10, it will be understood that such air will act as a form of fluid piston within the lower portion of the heating chamber and therefore, will serve to draw the cold air downwardly through the cold air ways afforded by the spacing of the jacket 10 from the sides of the vertical walls of the housing 1, hence setting up the so-called "forced draft" through the heating device and thereby generally lending to its efficiency.

The modus operandi of the invention may be reviewed as follows:

Electrical energy is, of course, conducted to the electrical resistance heating element 13. With the bringing of the heater 13 to proper temperature, it will be understood that air within the heating chamber or jacket 10 will be heated and by consequence, will be caused to ascend in the device, passing through the constricted way provided for by the frusto-conical sleeve 23. Such heated air will pass from the sleeve 23 into the atmosphere surrounding the device. Because of the arrangement of the cold air inlet ways in the heating device, together with the fact that the side walls of these ways are kept cool at all times by reason of the insulating material employed in their construction, it will be understood that cold air will pass in that direction as indicated by arrows in the Figure 1 downwardly through such cold air ways into the housing 1 of the device to a point adjacent the bottom thereof, whereupon it will be gradually heated, and hence, will ascend in that direction as further indicated by arrows, passing into and upwardly through the heating chamber or jacket 10 into final contact with the electrical resistance heating element 13 whereat it will be brought to the desired temperature and then discharged by way of the constricted outlet port provided by the frusto-conical sleeve 23 into the atmosphere. With discharge of the heated air from the constricted outlet way of the heating device, through the medium of the sleeve 23, it will of course cause such outgoing heated air to act as a form of fluid piston within the heating chamber, drawing or urging the air within the lower portion of such heating chamber in its path of ascension into engagement with the electrical resistance heating element 13. Thus, it will be appreciated that a forced draft will be provided as through the ways of the heating device and by consequence, the heating efficiency of the same will be generally increased. Also, because of the provision of the dissipating device 18, it will be understood that the heated air within the up-

per or intermediate portion of the heating chamber or jacket 10 will be prevented from heating the bottom of the device to too high a temperature whereat it would impede the passage and discharge of cold air through the cold air ways into such heating chamber.

In addition to being utilized as a heating device, it will be understood that the invention will serve as an effectual form of electrical cooking stove, this being attained merely by removing the drum-like cover or hood 21 from the top of the housing 1 and the jacket 10, thereby permitting a cooking utensil or other device to be brought into proximity to the electrical resistance heating element 13 and to the proper heating temperature.

Manifestly, the construction shown is capable of considerable modification, and such modification as is within the scope of my claims, I consider within the spirit of my invention.

I claim:

1. A heating device comprising a housing having heat insulating means arranged in the side and bottom portions thereof, a jacket supported within said housing in spaced relation to the inner sides and bottom of the same, heat insulating means for said jacket, and heating means supported adjacent the open upper end of said jacket.

2. A heating device comprising a housing, heat insulating means adjacent the inner sides and bottom portion of the housing, a jacket fixedly supported within said housing in spaced relation to the inner sides and bottom of the same, heat insulating means for said jacket, and an electrical resistance heating element spanning the open upper end of said jacket and fixedly supported with respect thereto.

3. A heating device comprising a housing, a jacket supported within said housing in spaced relation to the inner sides and bottom of the same, heating means supported adjacent the top of said jacket, and heat dissipating means fixedly arranged upon the bottom of said housing and positioned within and adjacent to the lower portion of said jacket.

4. A heating device comprising a housing, heat insulating means covering the inner sides of the vertical walls and bottom of said housing, a jacket supported within said housing in spaced relation to the inner sides and bottom of the same, heat insulating means for said jacket, heating means supported adjacent the top of said jacket, and heat dissipating means fixedly secured to the bottom of said housing and extending upwardly into the lower portion of said jacket.

5. A heating device comprising a housing, heat insulating means covering the inner

sides of the vertical walls and bottom of the bottom of said housing and extending said housing, a jacket supported within said upwardly into the jacket, a drum-like cover housing in spaced relation to the inner sides removably engageable over the upper end of the vertical walls of said housing, a grid and bottom of the same, heat insulating engaged over the upper open end of said 15 means for said jacket, an electrical resistance heating element spanning the open cover, and a frusto-conical ring fixedly carried over the upper end of said jacket and adjacent the open upper end of said 20 housing and extending upwardly therefrom, an inverted substantially frusto-conical heat dissipating means rigidly supported upon and for the purpose set forth.

In witness whereof I have hereunto set my hand.

THEODORE G. BAUGH.
